UNITED STATES PATENT OFFICE.

HERBERT CORRALL, OF HELENSBURGH, AND JAMES HEGGIE, OF CLYDEBANK, SCOTLAND, ASSIGNEES TO THE SINGER MANUFACTURING COMPANY, A CORPORATION OF NEW JERSEY.

HEMMING AND TRIMMING ATTACHMENT FOR SEWING-MACHINES.

1,339,742.

Specification of Letters Patent.

Patented May 11, 1920.

Application filed January 11, 1916. Serial No. 71,420.

To all whom it may concern:

Be it known that we, HERBERT CORRALL and JAMES HEGGIE, subjects of the King of the United Kingdom of Great Britain and Ireland, and residing, respectively, at 5 Helensburgh and Clydebank, both within Dumbartonshire, Scotland, have invented a certain new and useful Improvement in Hemming and Trimming Attachments for 10 Sewing - Machines, of which the following is a specification.

This invention has for its primary object to adapt a sewing machine for simultaneously hemming and trimming the raw edges 15 of felt hats and other articles.

To this end the invention provides a trimming attachment comprising a vertically reciprocating knife having a downwardly directed cutting edge and a coöperating 20 yieldingly mounted shearing blade movable relative to the knife and in a direction substantially parallel to the path of movement of the knife. The shearing blade is adapted to rest upon a body-fabric beneath an over- 25 turned hem so that the raw-edges of the hem may be sustained and trimmed smooth by the vertically reciprocated knife.

Figure 1 of the accompanying drawings is an end view of the head of a sewing machine 30 embodying the invention, showing the connections for operating the needle-bar and the usual vertically reciprocating cutter bar; Fig. 2 is a side elevation of the same; Fig. 3 is a plan of the trimming device.

As shown, there is fitted to the lower end 35 of the cutter bar 1, a bracket 2 formed as a yoke to the inner arm 3 of which is fixed a knife 4 constituting the upper trimming member and moving parallel to the needle path in advance of the needle 5, and to the outer arm 6 of which yoke is pivoted at 7' the carrier 7 for a shearing blade 8 coöperating with, and adapted to reciprocate in a direction substantially parallel to, the 45 knife 4, said carrier 7 being acted upon by a spring 9 tending to maintain the lower surface of the tilting shearing blade 8 in contact with the body of the work.

To suit different thicknesses of felt and 50 accommodate different widths of hem, it is necessary to provide for adjustment of the bracket 2, the upper trimming member or knife 4, and the lower trimming member or shearing-blade 8. Accordingly the bracket

2 is tongued and grooved as indicated at 2' 55 to a slide 11 which is seated in a groove 12 in the cutter-bar 1. Horizontal and vertical right line adjustment of the bracket relative to the bar is permitted by the slot-and-screw connections 13 and 14 provided for that purpose. The knife and the lower or shearing-blade 8 are each endwise adjustable by reason of their slot-and-screw connections 15 and 16, respectively, with the arm 3 and the carrier 7. 65

The cutter-bar 1 is actuated from the needle-actuating shaft substantially as described in the patent to Hill and Schramm, No. 668,184, February 19, 1901, from which it differs merely in fixing the lower limit 70 of the cutter-bar stroke, this being necessary so that the knife 4 will not descend closer to the throat-plate or work-support than the thickness of the thinnest material which is liable to be operated upon. As in said 75 patent the applicants' construction permits of elevating the trimming blades to an ineffective cutting position when stitching only is to be performed.

The presser-foot 17 is cut away on the left 80 hand or trimmer operating side of the needle for the obvious purpose of permitting the stitches being laid as close as desired to the trimmed edge of the hem. A feed-dog 18 having spaced fabric engaging portions 19 85 and 20 in front and rear of the needle respectively is arranged for coöperation with the presser-foot wholly to one side of the line of seam-formation where it cannot lift the lower blade 8 in operation. The front 90 fabric engaging portion is arranged directly opposite the lower trimming blade 8. By this arrangement and shape of the feed-dog and presser-foot it is very easy for the operator to simultaneously hem and trim the 95 edge of a felt hat especially when it has been creased preparatory for this operation and an edge-guide is arranged on the same side of the needle as the feed-dog.

In operation, the work is fed below the 100 carrier 7, the upper fold of the hem lying above the blade 8 and the width of the hem being determined by a guiding device 10 adjustably secured to the bed of the machine by a slot and thumb screw connection indicated at 21 and 22.

As the work is fed toward the needle 5, the knife 4 reciprocates and in coöperation

with the blade 8 trims the upper fold of the hem.

It will be understood that by virtue of the manner in which the knife 4 and blade 8 are mounted, the trimming device will operate with certainty irrespective of the thickness of the goods, without risk of cutting or marking the body of the hat or the like. It will also be understood that by virtue of the several adjustments for the bracket and blades of the trimming mechanism various thicknesses of material and widths of hem can be accommodated. It will also be noticed from the location of the pivot 7' at an elevation above the work-support approximately the same as the cutting edge of the knife 4, that the active portion of the lower trimmer member 8 which coöperates with the knife 4 will be constrained to move in a path substantially parallel with that of the movable blade 4. By this construction and arrangement of the carrier 7 for the lower blade relative to the upper blade 4 certainty of operation without interference is assured.

What we claim is:—

1. In a sewing machine having a throat-plate, a trimming attachment comprising a rectilinearly reciprocating knife having a downwardly directed cutting edge arranged substantially in parallelism with said throat-plate, and a coöperating spring actuated shearing blade adapted to reciprocate in a direction substantially parallel to the path of movement of said knife.

2. A trimming attachment for sewing machines comprising a vertically reciprocatory bar, a knife support movable with said bar, a knife participating in the vertical movements of said support, a shearing blade carrier pivoted to said support, a shearing blade sustained by said carrier and adapted to reciprocate in a direction substantially parallel to the path of movement of said knife, and a spring connection between said support and said carrier tending to tilt said shearing blade.

3. A trimming attachment for sewing machines comprising a reciprocatory cutter bar, a yoke attached to said bar and adjustable in vertical and horizontal directions, a knife fitted to one arm of said yoke, a spring-actuated carrier pivoted to the other arm of said yoke, and a tilting shearing blade fitted to said carrier.

4. In combination with a sewing machine having stitch-forming mechanism including a needle, a trimming mechanism for severing the raw edges of an overturned hem including a vertically reciprocating knife and a lower blade operatively controlled by the thickness of the underlying fabric for coöperating with said knife and shaped to permit the overturned margin of material to overlie its active edge portion, said knife

and blade having effective cutting edges located wholly in advance of the needle whereby a hem may be trimmed before it is stitched without impeding the travel or feed of the fabric.

5. In combination with a sewing machine, a trimming mechanism for severing the raw edges of an overturned hem including a vertically reciprocating knife, a pivoted lower blade spaced in operation above the work-support, and operatively controlled by the thickness of an underlying fabric for co-operation with said knife, the pivot for the lower blade being arranged in substantial parallelism with the line of feed.

6. In combination with a sewing machine having a work-support, a trimming mechanism for severing the raw edges of an overturned hem including a vertically reciprocating knife and a lower blade spaced in operation above said work-support and having an active edge-portion for co-operation with said knife, said active edge-portion being movable independently of said knife and in a path substantially parallel to the path of movement of said knife, and said lower blade being supported laterally of the line of feed substantially to one side of the line of seam-formation.

7. In combination with a sewing machine having a work-support, a trimming mechanism for severing the raw edges of an upper of superimposed layers of material and including a substantially vertically reciprocating knife and a lower blade having an active edge-portion coöperating with said knife, said lower blade having a pivot fixed relative to the knife, movable bodily therewith, and spaced laterally of the path of movement of the knife, whereby the lower blade may swing upon its pivot and its active edge-portion may move in a path substantially parallel to the path of movement of the knife.

8. In combination with a sewing machine having a work-support and stitch-forming mechanism including a needle, a trimming mechanism for severing the raw edges of an upper of superimposed layers of material including a cutter-bar, means for reciprocating said cutter-bar a less distance than the needle, a bracket carried by said cutter-bar, a pair of coöperating cutting members carried by said bracket and located above the work-support, one of said cutting members being movable independently and having an active ledger portion movable substantially parallel to the path of movement of the other cutting member, and means tending to separate said cutting members in a vertical direction.

9. In combination with a sewing machine having stitch-forming mechanism and a work-support, a cutter-bar, means for reciprocating said cutter-bar vertically, a

- bracket or yoke on said cutter-bar having a pair of arms, an upper trimming member secured to one of said arms, a carrier pivoted to the other of said arms and movable 5 in a vertical plane transverse the line of seam-formation, a lower trimming member secured to said carrier, the pivot of said carrier being located at substantially the same elevation above the work-support as 10 the cutting edge of said upper trimming member whereby the active edge of the lower trimming member is moved into co-operative cutting relationship with the upper trimming member when the latter descends against fabric interposed between the members.
10. In combination with a sewing machine having stitch-forming mechanism and a work-support, a cutter-bar, means for reciprocating said cutter-bar above the work-support, a yoke on said cutter-bar, a pair of relatively movable cutting members mounted on said yoke and means for adjusting said yoke bodily in a direction parallel to 20 the plane of the work-support whereby the margin between the trimmed edges and the line of seam-formation may be varied.
11. In combination with a sewing machine having stitch-forming mechanism and a work-support, a cutter-bar, means for reciprocating said cutter-bar above the work-support, a yoke on said cutter-bar, a pair of relatively movable cutting members mounted on said yoke, means for adjusting 30 said yoke toward and from said work-support whereby widely different thicknesses of material may be trimmed nicely.
12. In combination with a sewing machine having stitch-forming mechanism and a work-support, a cutter-bar, means for reciprocating said cutter-bar above the work-support, a yoke on said cutter-bar, a pair of relatively movable cutting members mounted on said yoke, means for adjusting said 40 yoke vertically and horizontally and means for adjusting said cutting members relative to the yoke.
13. In combination with a sewing machine having stitch-forming mechanism including a needle, a presser-foot and a feed-dog arranged on one side of said needle, a trimming mechanism for severing the raw edges of a hem including a pair of relatively movable cutting members arranged entirely 50 in advance of and on the side of said needle opposite said feed-dog and presser-foot, one of said cutting members being operatively controlled by the thickness of the body-fabric.
- 60 14. In combination with a sewing machine having stitch-forming mechanism including a needle, a work-support, a presser-
- foot, a feed-dog and an edge-guide arranged on the same side of the needle, a trimming mechanism including a vertically reciprocated knife and an independently movable shearing blade arranged for co-operation with said knife and controlled by the thickness of an underlying fabric, said trimming mechanism being located on the side of the 65 needle opposite said presser-foot, feed-dog and edge-guide, and said trimming mechanism being located above said work support.
15. In a trimming mechanism for sewing machines, a rectilinearly reciprocating knife 70 having a cutting edge, a yieldingly supported lower blade the plane of the body of which makes a substantial angle with the path of movement of the knife, said lower blade having a cutting edge parallel to that of the knife, means for relatively moving said knife and blade to sever material with the cutting edges in parallelism.
16. In a trimming mechanism for sewing machines, a rectilinearly reciprocating knife 75 having a cutting edge, a lower blade the plane of the body of which maintains a substantial angle with the path of movement of the knife, said lower blade having a cutting edge parallel to that of the knife, means for relatively moving said knife and blade to sever material without moving said cutting edge out of parallelism, said lower blade being controlled by the thickness of the underlying fabric during a trimming operation.
17. In a sewing machine having stitch-forming mechanism including a needle, a trimming mechanism comprising actuated cutting and ledger-blades disposed in planes intersecting each other at a substantial angle, the cutting edges of said blades being parallel.
18. In a sewing machine having stitch-forming mechanism including a needle, a presser-foot, a trimming mechanism supported independently of said presser-foot and comprising actuated cutting and ledger-blades disposed in planes intersecting each other at a substantial angle, the cutting edges of said blades being parallel.
19. In a sewing machine having a needle and work sustaining means, a trimmer comprising a pair of pivotally connected blades disposed at an angle to each other with their cutting edges maintained parallel with each other and with the plane of the work.
